WILLARD G. JACKSON, OF ROCKFORD, ILLINOIS.

SPARK-PLUG.

1,244,091.

Specification of Letters Patent. Patented Oct. 23, 1917.

Application filed March 1, 1917. Serial No. 151,624.

To all whom it may concern:

Be it known that I, WILLARD G. JACKSON, a citizen of the United States, residing at Rockford, in the county of Winnebago and State of Illinois, have invented certain new and useful Improvements in Spark-Plugs, of which the following is a specification.

This invention relates to improvements in spark plugs whereby a relatively large sparking chamber is provided, a large sparking surface is obtained therein and a clean sparking surface is maintained.

In the accompanying drawings, Figure 1 is a vertical sectional view showing in detail the construction of my improved spark plug. Fig. 2 is a sectional view taken approximately on line 2—2 of Fig. 1, showing the insulating core and the auxiliary ground terminal. Fig. 3 is an end view of Fig. 1. Fig. 4 is a similar view of Fig. 2.

The embodiment of my invention herein shown comprises a shell 1, a metal gland 2, an insulating core 3 of porcelain or the like, and terminals 4 and 5. The preferably metal shell 1 is externally threaded upon one end at 6 whereby it may be suitably secured in the combustion end of an engine cylinder. The opposite end of the shell is internally threaded to receive the gland or nut 2. The central opening or passage within the shell 1 includes two reduced portions 7 and 8, the narrowest portion 7 of the central opening being axially alined with the externally threaded portion 6 and the widest portion 9 carrying the internal screw threads. This reduction of the central opening provides two annular ledge or shoulder portions 10 and 11.

Within the gland and the shell and secured therebetween is the chambered insulating core 3 carrying the terminal rods 4 and 5. Upon the exterior of the core and rigid therewith is a projecting annular collar or flange 12 providing two annular faces 13 and 14, the face 13 coöperating with the annular shoulder 10, the other face, 14 coöperating with the inner end of the gland 2, said faces, shoulder, gland and shell rigidly securing the core 3 in the shell. Because of the difference in the coefficients of expansion of the shell and the core, the core is preferably made slightly smaller than the central passage in the shell and the gland. The gaskets 17 of any preferred material, such as copper, are between the coöperating faces and surfaces for suitably sealing the

joint between the core and the shell and for preventing the core from cracking or breaking under the pressure exerted by the gland when it is threaded into the shell to rigidly secure the core therein.

Eccentrically positioned upon the end of the core opposite the chambered portion is a longitudinal projection 18 rigid with the core. Axially alined within said projection and extending longitudinally through the core and the projection is a hole 19 parallel to the axis of the core and adapted to receive the terminal rod 4. A second hole 20 extends through the core body parallel to the hole 19 and carries the other terminal rod 5. The holes 19 and 20 are preferably located opposite each other, the axis of the core being approximately midway between. The rods 4 and 5 have enlarged end portions 21 with frusto-conical intermediate portions 22 which are seated in the corresponding enlarged portions 23 and 24, respectively, of the holes 19 and 20. These enlarged portions of the holes 19 and 20 communicate with the concentric annular chamber 25 in the core body. A cement packing 26 is placed between the bolts and core body to secure the bolts in the holes. The frusto-conical surfaces 22 and 24 of the bolt and the hole coöperate to seal the joint between the bolt and the core body. The opposite ends of the bolts are suitably secured to the core body as by the plain washers 27, the lock washers 28 and the nuts 29. With this construction, it will be noted that the clamping action and the sealing action of the bolt head or the equivalent thereof occurs at the widest part of the core body, thereby insuring sufficient material to prevent the core body shearing longitudinally or transversely. From the foregoing it will be apparent that the rod 5 may be and preferably is shorter than the rod 4 to secure better insulation between them. The longer rod 4

I have designated the current terminal and the shorter rod 5 the auxiliary ground terminal. The rod 4 carries a thumb nut 30 by which the current-carrying wire which is insulated from the motor frame may be secured to the rod. To the enlarged end of rod 4 is suitably secured the sparking wire 31 and to the rod 5 is similarly secured the wire 32. Each sparking wire is made of any suitable material which will not burn or fuse and comprises a securing portion 33 seated in a terminal rod, an intermediate portion

34 and a relatively long offset portion 35. The intermediate portions of the wires converge toward each other while the offset portions are parallel to the axis of the core body 5 and to each other. Herein I have shown the auxiliary ground wire 32 considerably longer than the current wire 31 and extending beyond the shell 1. Suitably secured to the shell and preferably opposite the current 10 wire and in line with both wires is the ground or base wire 36 which has an end portion extending equally close to the auxiliary ground wire 32 as the current wire 31 is distant therefrom. In this manner there 15 will be two spark gaps in the sparking circuit of equal width and a large sparking surface between the offset portions of the wires.

In operation it will be understood that 20 because of the large sparking surface provided a spark will always occur. Because of this large sparking surface the spark will be large and will burn any oil or carbon deposited on the sparking wires. If any carbon or oil should collect between the sparking wires 31 and 32 and short circuit them, which is unlikely because of the large sparking chamber provided, the spark will occur 25 between the wires 32 and 36 and at the same time the carbon or oil deposit which has 30 short-circuited the wires 31 and 32 will be burned out. In this manner certainty of operation is provided, efficient operation is assured because the sparking surfaces will 35 always be kept clean, and complete and instantaneous combustion is assured by the use of large sparking surfaces.

Although I have herein described in considerable detail the preferred embodiment 40 of my invention, I would have it understood that I do not intend to be thereby limited, but will be limited only by the scope of the appended claims.

I claim as my invention:

45 1. A spark plug having, in combination, a shell having an elongated passage with a reduced portion providing an annular shoulder, a core comprising a body portion having a chamber at one end axially alined with said passage, a collar portion between the ends of said body portion and rigidly secured thereto providing a pair of annular faces, one of said faces coöperating with said shoulder, and an eccentrically positioned 50 projection extending longitudinally from the body portion and opposite the chambered portion having a hole axially alined with said projection and extending through the core, the core having a second hole extending therethrough and parallel to said first mentioned hole, said holes communicating with the chamber, a terminal rod in each of said holes, the rod in said first mentioned hole being the current terminal and 55 longer than the auxiliary ground terminal

rod in the other hole, each of said rods having at one end an enlarged portion and a frusto-conical intermediate portion adapted to be seated upon a complementary conical surface in each hole, said contacting 70 conical surfaces lying approximately in the same plane as said collar portion, means upon the other end of said terminal rods for rigidly securing them in said holes, a 75 sparking wire carried by each of said rods having an intermediate converging portion and an elongated parallel portion within said chambered portion and said passage providing a large sparking surface therein, a ground terminal wire carried by said shell 80 extending proximately to said auxiliary ground wire, and a gland nut, the inner end thereof coöperating with the other of said faces to rigidly secure said core in said shell.

2. A spark plug having, in combination, 85 a shell, a chambered insulating core having an eccentrically positioned projection extending longitudinally therefrom and opposite the chambered portion having a hole axially alined with said projection and extending through the core, the core having a second hole extending therethrough and parallel to said first mentioned hole, a terminal rod in each of said holes, the rod in 90 said first mentioned hole being the live current terminal and longer than the insulated auxiliary ground terminal rod in the other hole, means for securing said rods in their respective holes, a sparking wire carried by each of said rods having an intermediate 95 converging portion and an elongated parallel portion within said chambered portion providing a large sparking surface therein, a ground terminal wire carried by said shell extending proximately to said 100 auxiliary ground wire, and a gland nut for rigidly securing said core within said shell.

3. A spark plug comprising, in combination, a shell having a reduced interior providing an annular shoulder, a chambered insulating core having a collar portion between the ends thereof providing a pair of annular faces, one of said faces coöperating with said shoulder, a terminal rod having an enlarged end portion and a frusto-conical intermediate portion and adapted to be seated in a hole extending longitudinally through the core, said hole having surfaces complementary to said enlarged and conical rod portions and being approximately in the 110 same plane as said collar portion, means for securing said rod in said core, and a gland, the inner end thereof coöperating with the other of said faces to rigidly secure said core in said shell.

4. A spark plug comprising, in combination, a shell, a chambered insulating core, a securing gland, a plurality of sparking terminals carried by said core and insulated from each other within the core, said termi- 125 130

nals comprising a rod and a wire having a body portion seated in said rod, an intermediate portion and an offset portion, said intermediate portions being inclosed within the core chamber and converging toward each other and the axis of said shell and said offset portions of said wires extending

parallel to each other and the axis of said shell, and a ground terminal sparking wire carried by said shell extending proximately 10 to one of said wires.

In testimony whereof, I have hereunto set my hand.

WILLARD G. JACKSON.
